UNITED STATES PATENT OFFICE.

THOMAS ABRAHAM BAYLISS, OF BIRMINGHAM, ENGLAND.

RAIL-JOINT.

SPECIFICATION forming part of Letters Patent No. 598,070, dated February 1, 1898.

Application filed September 15, 1896. Serial No. 605,885. (No model.)

To all whom it may concern:

Be it known that I, THOMAS ABRAHAM BAYLISS, manufacturer, a subject of the Queen of Great Britain, and a resident of Thirlmere, 5 Wheeley's Road, Edgbaston, Birmingham, in the county of Warwick, England, have invented an improved rail-joint for railways, tramways, and for such like connections, also applicable for building construction of all kinds 10 and for other purposes, of which the following is a specification.

My invention relates to rail-joints by which the ordinary fish-plates and bolts are dispensed with, the joint being formed entirely 15 without the use of bolts, screws, or like devices.

In the drawings, Figure 1 is a side view of a rail with the joint-block in place. Fig. 2 is a top view of the joint-block with the parts 20 separated. Fig. 3 is a similar view to Fig. 2 with the parts connected. Fig. 4 is an end view of the parts of Fig. 2. Fig. 5 is a side view of the main portion of the joint-block, and Fig. 6 is a side view of the removable 25 part of said block.

The rail A may be of any ordinary form, with the exception that at the meeting end each rail has a kerf or notch 1 in its web, these notches alining with each other and 30 forming a space into which projects the web portion D' of the plate D, forming one side of the joint-block. This plate is longer than the web portion D' and wider, so that its upper and lower edges may find support against

the flanges of the rail. On the opposite side 35 of the rail the joint-block is completed by a removable plate D³, having a dovetail groove D⁴ in its inner side adapted to slide upon a dovetail rib or projection D² on the web portion D'. The plate D³ is substantially like 40 the plate D in extent, and the upper and lower edges thereof find bearings against the flange portion of the rails, and from this construction it will be seen that the joint-block makes a solid and firm connection between 45 the rails at their meeting ends, bridging the joint and resisting all movement of the rail ends vertically. The dovetail groove D⁴ in the face of the plate D³ does not extend from end to end of the said plate, but ends at a 50 point D⁵, where the stop-shoulder is left to limit the position of the removable plate.

I claim as my invention—

A rail-joint comprising the rails having the slotted end and a joint-block having a plate 55 D on one side, a web D' extending therefrom and adapted to pass through the slots and a removable plate D³, the said removable plate and web being connected by a tongue and groove which groove extends along the face 60 of the plate and ends at a stop-shoulder D⁵, substantially as described.

In witness whereof I have hereunto set my hand in presence of two witnesses.

THOMAS ABRAHAM BAYLISS.
